UNITED STATES PATENT OFFICE.

FRANK KUHN, OF DETROIT, MICHIGAN.

ELECTRICALLY-HEATED SAD-IRON.

1,096,929.

Specification of Letters Patent. Patented May 19, 1914.

Application filed October 5, 1912. Serial No. 724,169.

To all whom it may concern:

Be it known that I, FRANK KUHN, a citizen of the United States of America, residing at Detroit, in the county of Wayne and State of Michigan, have invented certain new and useful Improvements in Electrically-Heated Sad-Irons, of which the following is a specification, reference being had therein to the accompanying drawings.

10 The invention relates to electrically-heated sad irons and consists in the novel construction as hereinafter set forth.

In the drawings: Figure 1 is a longitudinal section through the iron. Fig. 2 is a perspective view of a portion of the base showing the manner of securing the heat-distributing plate and electrical connections. Fig. 3 is a perspective view of a portion of the heat-distributing plate.

20 A is the base formed of a flat plate of metal, having parallel top and bottom faces; and B are threaded studs engaging correspondingly threaded apertures in said base and projecting vertically therefrom.

25 C is an electrical heating unit comprising a suitable resistor—such as a flat ribbon, wound upon a flat insulator core. D is a heat-distributing and clamping plate extending over substantially the full area of 30 said heating element and of equal thickness to the base A. This distributor is apertured for engagement with the studs B, and is clamped by nuts E engaging said studs.

F are terminal contacts for the heating unit which are secured to an insulator block G, and the latter is secured by a metal socket holder H having a laterally-extending plate I, resting upon the distributing plate D. The plate I is slotted for engagement with 40 the stud B and is clamped in position by the same nut E which secures the distributing plate to the base. The holder is further secured in position by the engagement of the plate I with a recess J in the upper face of 45 the distributing plate D, which prevents twisting or lateral displacement of the insulator G.

K is a hood inclosing the heating element and the distributing plate and resting upon 50 the margin of the base plate A. This hood is cut away at L for the passage of the insulator block G and the terminal contacts F projecting therefrom.

M is a bail-shaped frame for the handle N, 55 said frame being secured to the studs B by nuts O thereon, and being held out of heat-

conducting contact with the hood by flanged washers P surrounding said studs.

Q is a guide socket for receiving the plug of the external connector, and guiding the 60 same into engagement with the contacts F.

With the construction as described, to assemble the parts the heating unit with the terminals F and insulator block G attached thereto, is first placed on the base A, being 65 sleeved upon the studs B. The distributing plate is then placed in position, this being permitted by turning back the block G and its securing holder H so as to provide clearance for the plate D, after which said parts 70 are turned back and the shank I is secured by the clamping nuts E. When secured in position the hood may be placed upon the base; and the nuts O engaged with the studs B will simultaneously secure the handle M 75 and hood K to the base.

What I claim as my invention is:

1. In an electrically-heated sad iron the combination of a base plate, a superposed, heat-distributing plate and interposed, flat 80 heating-element, terminal connections for said element, an insulator block through which said terminals pass, a supporting shank for said block, overlying said distributing plate, and a screw forming a common 85 clamping means for said shank, heat-distributing plate, heating-element and base plate.

2. In an electrically-heated sad iron, the combination of a base plate, a superposed, 90 heat-distributing plate and interposed heating-element, terminals for said heating-element, an insulator block for said terminals, a supporting shank for said insulator block, overlapping said heat-distributing plate, a 95 threaded stud projecting upward from said base plate and passing through said heating-element, heat-distributing plate and shank, a nut engaging said stud to clamp said parts together, a hood for inclosing said heat-distributing plate and heating-element, apertured for the passage of said insulator block, a handle, and a clamping nut engaging an extension of said stud for securing said handle and hood to said base. 100

3. An electrically-heated sad iron comprising a base plate, a superposed, heat-distributing plate and interposed heating element, studs projecting upward from said base plate and passing through said heating 110 element and heat-distributing plate, a hood inclosing said heating-element and heat-dis-

tributing plate, supported upon said base plate and engaging said studs, a handle also engaging said studs and together with said hood clamped thereby to said base, terminals 5 for said heating element, an insulator block supporting said terminals, passing outward through an aperture in said hood, a shank for supporting said insulator block, engaging said stud, and a clamping nut on said 10 stud for simultaneously clamping said shank, heat-distributing plate and heating-element to said base.

4. An electrically-heated sad iron comprising a base, a superposed heat-distributing plate and interposed heating-element, 15 studs projecting upward from said base, through said heating-element and heat-distributing plate, a hood engaging said studs, a handle having a bail-shaped frame also 20 engaging said studs, heat-insulating washers upon said studs between said handle and hood, clamping nuts upon said studs for securing said handle and hood to said base, a plug socket secured to said handle, terminals 25 for said heating-element projecting upward into said plug socket, an insulator block supporting said terminals, passing through an aperture in said hood, a shank for supporting said insulator block, and a clamping nut 30 on one of said studs for simultaneously clamping said shank, hood, distributing element and heating element to said base.

5. In an electrically-heated sad iron the combination with a base of a superposed, 35 heat-distributing member, an interposed heating-element, terminals for said elements flexibly connected thereto, an insulator block for supporting said terminals, a shank for said block normally overlapping said heat- 40 distributing plate, a stud projecting upward from said base and passing through said heating-element, heat-distributing plate and shank, and a nut on said stud for simultaneously clamping said parts.

45 6. An electrically heated sad iron, comprising a base, a superposed, heat-distributing member, a heating-element, terminals for said elements flexibly connected thereto, an insulator block connected to said terminals, a laterally-extending shank on said block, normally overlapping said heat-distributing plate, a stud projecting upward from said base and passing through said heating-element, heat-distributing plate and 50 said shank, and a nut engaging said stud for clamping said parts.

7. In an electrically-heated sad iron, the combination with the base plate of a superposed, heat-distributing plate and interposed heating-element, a stud projecting upward from said base through aligned apertures in said heating-element and heat-dis-

tributing member, terminals for said heating-element flexibly connected thereto, an insulator block secured to said terminals, a 65 laterally-extending shank on said insulator block, normally overlapping said heat-distributing plate and slotted for engagement with said stud, and a nut engaging a threaded portion of said stud for clamping said 70 shank, heat-distributing plate and heating-element to said base.

8. In an electrically-heated sad iron, the combination with a base of a superposed, heat-distributing plate and interposed heating-element, a stud projecting upward from said base through registering apertures in said heating-element and heat-distributing plate, terminals for said heating-element flexibly connected thereto, an insulator block 80 secured to said terminals, holding the same in fixed relation to each other, a laterally-extending shank for said block, overlapping and engaging a recess in said heat-distributing plate, and slotted for engagement with 85 said stud, and a nut engaging said stud and clamping said shank, heat-distributing plate and heating-element.

9. In an electrically-heated sad iron the combination with a base of a superposed 90 heat-distributing plate and interposed heating-element, a hood inclosing said heat-distributing plate and heating-element, a handle above said hood, a stud passing through aligned apertures in said heating-element, 95 heat-distributing element, hood and handle, terminals for said heating-element flexibly connected thereto, an insulator block to which said terminals are fixedly attached, engaging an aperture in said hood, a shank 100 for said block, overlying said heat-distributing plate and slotted to engage said stud, and clamping nuts upon said studs for respectively clamping said shank, heat-distributing plate, heating-element and said handle and hood to said base.

10. In an electrically-heated sad iron, the combination with a base heating element and a hood, of a terminal connected to said heating element projecting upward through 110 an aperture in said hood, an insulator block secured to said terminal and engaging said aperture, a handle having a bail-shaped frame secured to said base, and a guide adapt to receive a removable plug secured 115 to the rear side of said bail and inclosing said terminal.

In testimony whereof I affix my signature in presence of two witnesses.

FRANK KUHN.
